SHEET METAL PRESS

Filed Sept. 3, 1930

Inventor:
Otto Kühner
by Kartekichan's
Atty.

UNITED STATES PATENT OFFICE

OTTO KÜHNER, OF COPPINGEN, GERMANY

SHEET METAL PRESS

Application filed September 3, 1930, Serial No. 479,433, and in Germany September 4, 1929.

My invention relates to sheet-metal presses, and more particularly to the blank holders of such presses. In my copending application for patent of the United States, Serial No. 448,676, filed April 30, 1930, I have described a press in which the blank holder is fitted to slide in a cavity of the drawing slide against the action of an air cushion, as shown in Fig. 2 of my said copending application.

It is an object of my invention to so design a device of this type that it is suitable for presses having a comparatively wide drawing slide, for instance, presses for drawing mud guards for motorcars, window frames and the like. To this end, instead of arranging the blank holder in, I arrange it on the drawing slide, and provide means for entrapping a fluid cushion between the drawing slide and the blank holder.

In this manner not only the press may be designed for any width but I also dispense with the packing for guiding the blank holder in the drawing slide and furthermore I may provide some play between the blank holder and the drawing slide so that the blank holder is free to adapt itself to variations in the thickness of the blank material and exert uniform pressure on the blank throughout.

In the drawing a sheet-metal press embodying my invention is illustrated diagrammatically by way of example, the drawing showing a partly sectional elevation of the press.

Referring now to the drawing, *a* is the main driving or crank shaft of the press, *b* are its pitmen, *d* is the drawing slide, and *c* are ball joints connecting the pitmen *b* with the drawing slide *d*. *e* is the drawing block, *m* is a blank, and *f* is the blank holder which engages the edge of the blank *m* and holds it down on the drawing block *e*. *o*, *o* are brackets extending from the sides of the blank holder *f*, and *n*, *n* are slide bars on which the brackets are guided. Similar brackets *p*, *p* are provided on the sides of the drawing slide *d* extending through slots in the sides of the blank holder *f* and also guided on the bars *n*.

f' is a flange projecting inwardly from the blank holder *f*, and *g* are pneumatic cylin-

ders secured on the flange. Two cylinders are shown by way of example but obviously any number of cylinders may be provided. Each cylinder is equipped with a piston *h* and a piston rod *i* which extends through a bore and a packing *l* in the flange *f'*, and *m'* is a spherical joint at the lower end of each piston rod by which it is connected to the drawing slide *d*. *k* are passages connecting the space below the piston *h* in each cylinder *g* with a compressed-air reservoir, not shown.

In the position illustrated the drawing slide *d* is at the lowermost end of its stroke, and the blank holder *f* is held on the edge of the blank by the pressure of the air below the pistons *h*. When the drawing slide *d* is reversed to move upwards the blank holder *f* is still held down on the edge of the blank by the air pressure, although the pressure is somewhat reduced by the increase of volume it has undergone. Finally the drawing slide *d* engages below the flange *f'* and entrains the blank holder *f*. When the drawing slide is reversed for another downward stroke the blank holder *f* moves down with the drawing slide until it strikes the edge of the blank *m* on the drawing block *e* and is arrested, while the drawing slide moves on, compressing the air below the pistons, expelling it partly into the reservoir, not shown, through the passage *k*, and forging the blank *m* into the shape indicated.

As shown, the drawing slide *d* is fitted into the blank holder *f* with some play so that the blank holder is free to edge slightly if the material of the blank is not of quite uniform thickness. Its edging is facilitated by the ball joints *m'* at the lower ends of the piston rods *i*. It will be understood that the blank holder is not guided on the drawing slide but is guided on the bars *n*. Obviously, however, the guiding means must not interfere with its edging.

I wish it to be understood that I do not desire to be limited to the exact details of construction shown and described for obvious modifications will occur to a person skilled in the art.

In the claims affixed to this specification no selection of any particular modification of

the invention is intended to the exclusion of other modifications thereof and the right to subsequently make claim to any modification not covered by these claims is expressly reserved.

I claim:

1. A sheet-metal press comprising a drawing slide, adapted to perform its operation in a single stage, means for reciprocating said drawing slide, a blank holder surrounding said drawing slide, a cylinder on said blank holder, a piston in said cylinder, and a piston rod connecting said piston to said drawing slide.
- 15 2. A sheet-metal press comprising a drawing slide, a blank holder so arranged on said drawing slide as to move freely within limits with respect to said drawing slide, means for reciprocating said drawing slide, and pneumatic means operatively connecting said blank holder to said drawing slide.
- 25 3. A sheet-metal press comprising a drawing slide, means for reciprocating said drawing slide, a blank holder surrounding said drawing slide at a clearance so as to move freely within limits with respect to said drawing slide, a cylinder on said blank holder, a piston in said cylinder, a piston rod on said piston, and a universal joint connecting said piston rod to said drawing slide.
- 30

In testimony whereof I affix my signature.

OTTO KÜHNER.
